UNITED STATES PATENT OFFICE.

GEORGE M. HUBBARD, OF NEW HAVEN, CONNECTICUT, ASSIGNOR TO
W. & E. T. FITCH, OF SAME PLACE.

DESIGN FOR A HARNESS-TERRET.

SPECIFICATION forming part of Design No. 16,478, dated January 19, 1886.

Application filed November 23, 1885. Serial No. 183,789. Term of patent 7 years.

To all whom it may concern:

Be it known that I, GEORGE M. HUBBARD, of New Haven, in the county of New Haven and State of Connecticut, have invented a new 5 Design for Harness-Terrets; and I do hereby declare the following, when taken in connection with accompanying drawing and the letters of reference marked thereon, to be a full, clear, and exact description of the same, and 10 which said drawing constitutes part of this specification, and represents a face view.

This invention relates to a design for that part of a harness-saddle through which the reins are guided, and what are commonly 15 known as "terrets;" and the design consists in the configuration as hereinafter described, and as shown in the accompanying drawing.

The base *a* extends upward and terminates in the form of a sphere, *b*, from opposite points 20 of which extends an arm, each of said arms

terminating in spherical ends *c d*. From the said ends the sides *e f* rise, curved outwardly, and then returned, meeting at the center to form the eye. The eye may be of any desired form without departing from the design, the 25 essential feature of which is the three connected spheres *b c d*, which form the bottom of the eye.

I claim—

The herein-described design for harness-terret consisting of the base *a*, extended upward and terminating in a sphere, *b*, from opposite points of which extends an arm, each of said arms terminating in spherical ends *c d*, and with an eye extending upward from said 35 spherical ends, as described and shown.

GEORGE M. HUBBARD.
